UNITED STATES PATENT OFFICE

2,024,457

PISTON SKIRT EXPANDER

James Kourimsky, Chicago, Ill.

Application March 26, 1935, Serial No. 13,090

3 Claims. (Cl. 309—12)

This invention relates to that type of trunk pistons of internal combustion engines in which the slotted skirt of the piston is provided with means for effecting a resilient expansion of the same, and with means for limiting in an adjustable manner the expansion of the piston skirt and this improvement has for its object:

To provide a structural formation and combination of parts in an expander device for the slotted skirt portion of a trunk piston of a simple, compact and economical form, adapted to resiliently act on the slotted skirt portion of the piston, and by means of which the extent of expansion of the piston skirt can be readily and effectively attained so as to regulate the frictional contact between the piston and the inner wall of an engine cylinder, all as will herein-after more fully appear.

In the accompanying drawing:

Fig. 1 is a central sectional elevation on line 1—1 Fig. 2 of a trunk piston to which this invention is applied.

Fig. 2 is a horizontal section of same on line 2—2 Fig. 1.

Fig. 3 is an enlarged detail section on line 3—3 Fig. 1.

Fig. 4 is a detail sectional elevation on line 4—4 Fig. 3.

Fig. 5 is a detail sectional elevation on line 5—5 Fig. 4.

Fig. 6 is a side elevation of a modified form of the device.

Fig. 7 is a detail section of same on line 1—1 Fig. 6.

Like reference numerals indicate like parts in the different views.

This invention is shown in the drawing as applied to a piston of the trunk type, the skirt portion 1 of which is rendered expandable by a longitudinal slot 2, usually of T-shape as shown.

In this improvement the skirt portion 2 is formed with receiving orifices 3 in adjacent relation to the opposed margins of the slit 2 thereof for holding engagement with the attaching pins or studs of the device for producing a resilient expansion of the piston skirt and the adjustable control of the extent of such expansion as the judgment of the operator may suggest. Said device comprising a detail construction of parts, 50 as follows:

Said device comprising a pair of substantially counterpart blocks or heads 4 and 5 arranged in opposed relation and of an approximately rectangular shape, with an inner face of each head provided with a fixed or integrally formed

attaching pin or stud 6 adapted to engage in an aforesaid hole or orifice 3 of the piston skirt to hold the device in proper operative position during actual use.

In the preferred form of this invention shown 5 in Figs. 1 to 5 inclusive, the heads 4, 5, are formed with pairs of socket recesses 4' and 5' in their opposed faces for the reception of end portions of a pair of compression springs 7 of the spiral type, the resilient tendency of which 10 is to force the heads 4, 5, apart, to in turn cause a corresponding resilient expansion of the piston skirt 1.

Intermediate of the aforesaid socket recesses 4', 5', the heads 4 and 5 are formed with aligned 15 passages in parallel relation to said socket recesses, adapted to receive the shank portion of a screw bolt 8, the fixed head 9 of which has bearing on an outer and remote face of one head or block and is held from independent turning 20 by contact of said bolt head with a fixed rib 10 on the head or block.

The adjustable nut 11 has bearing on the outer and remote face of the companion head or block and may be held from accidental turning 25 movement during actual use by any ordinary nut locking provision.

With the above described construction, the device can be adjusted as required to regulate the range of expansion of the piston skirt 1 under the influence of the springs 7 to attain the desired resilient contact of the piston skirt with the inner wall of the engine cylinder with an avoidance of wear due to an excessive expansion 30 of the springs 7 when not restricted by means 35 controlling the resilient expansion thereof.

In the modified form of the invention shown in Fig. 6 and 7, a single expansion spring 7' is arranged at the center of the pair of heads or 40 blocks in a manner similar to that described in connection with the preferred form of the invention, with a pair of screw bolts 8' arranged at opposite sides of said spring and adapted to effect the desired regulation of the parts. 45

Having thus fully described my invention, what I claim as new, is:—

1. The combination with a trunk piston, the skirt portion of which is slotted for expansion purpose, and in which the margins of the slit 50 are provided with receiving orifices, a pair of expander heads each provided with an attaching stud for engagement in a receiving orifice of the piston skirt, and with socket recesses in their opposed faces, expansion springs arranged in 55

said socket recesses, and an adjustable screw bolt extending through said heads and adapted to regulate the degree of expansion between said heads and corresponding expansion of the piston skirt.

2. A trunk piston as specified in claim 1 wherein the pair of expander heads are each formed with a pair of socket recesses in spaced relation, and a single regulating screw bolt ex-

tending through the pair of heads midway between the pair of socket recesses.

3. A trunk piston as specified in claim 1, wherein one of the pair of expander heads is provided with an upstanding rib having adjacent relation to the fixed head of the adjusting screw bolt and adapted to hold the same from a turning movement in actual use of the piston.

JAMES KOURIMSKY.
